(57) **CLAIM**

The ornamental design for the laptop support device, as shown and described.

DESCRIPTION

FIG. 1 is a perspective view from above of a laptop support device in accordance with our design;

FIG. 2 is a first side view of the laptop support device in accordance with our design;

FIG. 3 is a second side view of the laptop support device in accordance with our design;

FIG. 4 is a top plan view of the laptop support device in accordance with our design;

FIG. 5 is a bottom plan view of the laptop support device in accordance with our design;

FIG. 6 is a third side view of the laptop support device in accordance with our design; and,

FIG. 7 is a fourth side view of the laptop support device in accordance with our design.

The broken lines representing environmental structure are for illustrative purposes only and form no part of the claimed design.
